G. E. WHITING

CONDENSER ATTACHMENT

Filed Sept. 18, 1926

INVENTOR.
GEORGE E. WHITING.
BY
Richard S. Dunn
ATTORNEY.

UNITED STATES PATENT OFFICE.

GEORGE E. WHITING, OF BROOKLYN, NEW YORK.

CONDENSER ATTACHMENT.

Application filed September 18, 1926. Serial No. 136,323.

This invention relates to condensers for use in wireless, radio and other electrical circuits and appliances.

A particular object of the invention is to combine with a variable condenser, a supplementary condenser of the fixed variety, the aim being to supply a supplementary condenser of fixed variety to a variable condenser of comparatively small capacity, the 10 supplementary condenser representing the bulk of the capacity required in the combination, except when the total capacity required is very small, in which case, the capacity of the fixed unit in the combined instrument might be smaller than that of the variable unit to which it is coupled.

A further particular object of the invention is to provide a coupled unit consisting of a variable and fixed condenser having 20 suitable parts, extensions or fittings which shall enable a fixed condenser and a variable condenser to be instantly coupled in parallel and the fixed condenser instantly removed or replaced by another of different 25 capacity, as a needed change of capacity is required.

A further particular object of the invention is the provision of means for coupling a variable and a fixed condenser so that the 30 variable condenser is made variable within all practical or necessary limits by the addition thereto of a fixed condenser of suitable capacity.

To enable others skilled in the art to 35 fully comprehend the underlying features of my invention that they may embody the same in the various modifications in structure and relation contemplated, a drawing depicting a preferred form has been annexed 40 as a part of this disclosure and in such drawings, similar reference characters denote corresponding parts throughout all the views, of which,

Figure 1 is a view in sectional elevation 45 showing the variable condenser having secured thereto a fixed condenser, the connection forming the main essential of my invention.

Figure 2 is a rear view in elevation of the 50 variable condenser showing the arrangement thereon of the fixed condenser.

Figure 3 is a sectional view in detail taken 55 on the line 3-3 of Figure 2, showing the connection post which secures the fixed condenser to the variable condenser.

Figure 4 is a fragmentary view of the

variable condenser showing in connection therewith, a means for holding a condenser of the fixed type.

Figure 5 is an end view of the fixed condenser shown in Figure 4 and its method of connection to the variable condenser.

Figure 6 is a view similar to Figure 4 showing a modified form of attaching a condenser cartridge to the variable condenser.

Figure 7 is a view in side elevation of the cartridge type of condenser showing the construction of the ends thereof which are adapted to engage the variable condenser.

Figure 8 is a view similar to Figure 6 showing a still further modified form of fixed condenser holding device, and

Figure 9 is a view in perspective of one of the holding plates arranged in connection with the variable condenser to maintain the fixed cartridge condenser in its place.

Variable condensers have been made heretofore, consisting of alternate plates of metal, some of which are fixed and some of which are movable. Where small electric 80 capacity is desired in the variable condenser, the condenser itself may be kept small in size and weight, but where a moderate capacity is necessary, the variable condenser becomes both heavy and bulky, not to say 85 costly. Condensers of the fixed variety, however, which are composed of thin metal plate bound together by suitable insulating means and carried between two end metallic binders, are small in weight, bulk and cost 90 and can be made up without increasing the bulk or weight, to any capacity desired.

If a small capacity variable condenser is always used with a fixed capacity condenser attached thereto in parallel, the mean capacity required for the circuit or work in hand can be obtained by selecting a suitable component of the fixed variety; and a small variable condenser coupled thereto will always give the fine adjustment required for 100 precision of effect in working. It is common knowledge that two fixed condensers placed in parallel have a capacity equal to the sum of their respective capacities and such use has often been made of fixed condensers by both amateurs of ability and others but I propose to alter the value of a variable condenser by the addition of a fixed condenser and the rendering of this, a permanent possibility with facility in operating 105 by provision of suitable fittings and fixed condensers suitably made for such use, thus

enabling an immediate change to be made in the total capacity of the combined condenser by the simple removal of one fixed condenser and the substitution of another of 5 smaller or greater capacity, as desired.

Variable condensers, at present, are only variable up to their nominal greatest capacity, but my invention makes them absolutely variable within all practical or necessary 10 limits.

Referring to the drawings, and particularly Figures 1 and 2, it will be noted that I have provided, in connection with the usual variable condenser, which comprises 15 the dial 5, back and front boards or panels 6 and 7 and fixed and movable plates 8 and 9 respectively, the latter being carried upon a suitable rotor 10 and the fixed plate being carried on suitable bolts 11, one of the 20 bolts 11 and the rotor 10 being in electrical circuit as shown by the connector strips 12, which are secured at their ends, one to the rotor shaft 10 and the other to one of the fixed plate carrying bolts 11, these connectors 25 12 are positioned on the rear panel 7 and, as shown in Figure 2, are joined at their ends by a fixed condenser 13, which is made up of any suitable dielectric material positioned between suitable metallic bands 30 or strips as is common in the construction of fixed condensers of the cartridge type. The ends of the connectors are positioned between the bottom end of the clips 14 and the panel 7. The clips being held in position 35 through the medium of the suitable screws 15 and one of these clips 14 being positioned at each of the ends of the connectors so that when a fixed condenser is positioned in the ends of the clips, an electrical circuit is 40 formed through the fixed condenser and also through the variable condenser.

The method of holding the fixed condenser in position is particularly the substance of my invention and in Figure 3, the 45 clip 14 is composed of a bifurcated, up-standing piece of metal, the bifurcated portion of which forms spring jaws into which the fins, formed on the ends of the fixed cartridges are held, to securely position the 50 fixed cartridge in position in circuit with the variable condenser.

In Figure 4, I have shown a different type of holding means which consists in providing one of the fixed bolts 11 of the variable condenser with an extended threaded portion 17, which is adapted to engage the interiorly threaded end of a sleeve 18 which acts as a nut to grip the connector strip 12 between it and the panel 7. The cartridge in 55 this instance is provided with end fins 16 in which is formed eyelets, the eyelets carrying therein the beaded ends of the clip members 17, which are formed with yieldable jaws 18, which have a tendency to expand 60 outwardly to engage the inner walls of the

sleeves 18 to hold the fixed cartridge condenser in place. It of course will be readily seen that the cartridge condenser is removable at will by drawing the same away from the panel 7. In order to provide for the 70 opposite fastening of the fixed condenser in Figure 4, so that the contact may be made directly through the rotor, I provide a flanged sleeve member 19 which is held in position against the panel 7 through the 75 medium of the nut 20, the latter also acting to retain the connector 12 about the sleeve 19 and against the panel 7.

In Figure 6, I have shown a still further modified form of connecting the fixed condenser cartridge to the fixed and variable condenser post and as shown, the end of the fixed post 11 is extended and slotted as at 21 to provide spring jaws which are adapted to pass through the eyelet 21 formed in the 80 fin 16 on the end of the cartridge condenser 13. These eyelets are provided in the fins on either end of the cartridge and the rotor shaft of the variable condenser is extended as at 22 and slotted to provide a holding 85 clip which engages the opposite end of the condenser and frictionally holds the same in position, as shown. The reduced end 22 of the variable condenser rotor 10 is housed in a suitable sleeve 23 over which is threaded 90 a nut 24 to retain the connector 12 in position. It is of course understood that these connectors are the medium of bringing the 95 circuit into the condenser and varying the capacity of the circuit. 100

In Figure 8, I have shown an additional modification which consists in extending the fixed condenser post 11 and threading the same beyond the panel 7 to receive the nut 25, the nut holding in place the connector 12 and also a substantially L-shaped bracket 105 26, in the outer end of which is provided an opening 27 to receive the nose-like end 28 of the fixed cartridge condenser 29. The opposite end of the condenser is held in a 110 similar bracket 26, the inner end of which is provided with an opening through which passes a threaded sleeve 30, the nut 31 being threaded over the sleeve to hold the bracket 26 in place and also the usual connectors 12. 115 It is evident therefore, that the upstanding portions of the brackets 26 can be made of spring metal so that the nose-like end 28 of the cartridge condenser 29 will spread the same apart so that the condenser may be 120 snapped into position and retained in the opening 27 formed in said bracket.

It is evident therefore, that I have provided several advantageous methods of combining a fixed and variable condenser whereby the capacity may be changed as desired and that I have also provided an inexpensive means of combining variable with fixed condensers so that the same may be used in combination without greatly increasing the 125 130

cost of the electrical fixture, as a whole, of which the condenser forms a part.

It is evident, also, that I have provided a means of altering the value of a variable condenser by the addition thereto of a fixed condenser and the rendering of this combination with a minimum of time, labor and number of parts necessary.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. The combination with a variable condenser of a fixed condenser, the variable condenser having a panel, retaining extensions on said panel, and the fixed condenser being arranged to be releasably held in said retaining extensions, and means for completing a circuit through the variable and fixed condenser.
2. In combination, a variable condenser comprising movable and fixed plates, post

members for holding said plates, sleeves associated with said post members, a fixed condenser provided with resilient sleeve engaging extensions whereby the fixed condenser can be releasably secured to said sleeves.

3. The combination with a variable condenser of a fixed condenser, and gripping extensions on said variable condenser for releasably holding the fixed condenser in position and means for completing a circuit through both the fixed and variable condensers.

4. The combination with a panel of a variable condenser of a plurality of yieldable retaining members, a fixed condenser, and eyelets on the ends of said fixed condenser for releasably engaging said retaining members.

5. In electrical condensers, the combination with a variable condenser having a plurality of fixed and movable plates, posts supporting said fixed and movable plates, and insulating members carrying said posts, of a plurality of yieldably holding arms carried by one of the insulating members and holding sleeves adjacent said posts for receiving the holding arms whereby the fixed condenser is releasably held in position on said variable condenser.

In testimony whereof I affix my signature.

GEORGE E. WHITING. [L.S.]
